UNITED STATES PATENT OFFICE

WALTER RICHMOND, OF CLEVELAND, OHIO

APPARATUS FOR RECORDATION AND REPRODUCTION OF SOUND

Original application filed March 12, 1920, Serial No. 365,320. Divided and this application filed December 6, 1930. Serial No. 500,661.

This invention relates to a method and apparatus for translating sound and is in the nature of a divisional application of my co-pending application Serial No. 365,320, filed March 12, 1920, on an apparatus for translating sound.

This invention relates to a method of and apparatus for translating sound. Heretofore in the translation of sound waves considerable difficulties have been experienced in recording and reproducing sound waves clearly.

These various difficulties, their causes and effects, and the manner in which I have overcome them and made possible true and clear recordation and reproduction of sound of controlled volume will become apparent from the following specification.

One object of my invention is to eliminate undesirable vibrations of various parts of the recording or reproducing apparatus, to record and reproduce the original sound waves clearly and to reduce distortion or interference of other waves.

Another object of my invention is to reproduce the original sound waves and at the same time eliminate all other sound waves which from various causes inherent in present reproducers find their way into the amplifying devices of commercial translating devices and mingle with the original sound waves to an objectionable extent.

Another object of my invention is to translate one class of waves into equivalent waves of another class and to retranslate from this class into the original class of wave in a manner such that the final wave suffers no serious deterioration from its several translations.

Another object of my invention is the substantial translation of sound waves into their equivalent mechanical or electrical waves or the reverse, the translation of mechanical or electrical waves substantially into their equivalent sound waves without a noticeable addition or introduction of interfering waves.

Another object of my invention is to produce a diaphragm so delicately poised that it will respond to very slight variation in tone or magnitude of vibration and which is

at the same time so constructed and actuated that it can swing through a greater amplitude than the greatest amplitude of vibration to which it will be subjected in use, thus enabling the reproduction of sound waves of greater volume than the original waves free from noticeable distortion in tone or clearness.

Another object of my invention is a diaphragm which will not lag appreciably behind the impressed vibration but will reach the limit of its greatest vibration substantially in unison with the impressed vibration and which will return to its normal position as rapidly as the cycle of the particular tone which is being impressed.

Another object of my invention is a diaphragm, different portions of which have different periods of vibration or different key notes.

Another object of my invention is a diaphragm which, as a whole, has no key note.

Another object of my invention is to obtain clear enunciation in the translation of sound waves.

Another object of my invention is to improve the reproduction of the human voice and other tones and to reduce the harsh, metallic, mechanical sounds such as are produced by many commonly used translating devices.

Another object of my invention is to record and reproduce sound waves so that they have substantially the same volume as the original sound waves without seriously impairing the quality of tone or enunciation as distinguished from various expediencies which have been in use, such as the fibre needle which produces fairly good tones but of such low volume as to be undesirable.

Other novel features of my invention are described and claimed in the co-pending application above referred to and in my co-pending application, Ser. No. 500,660, filed December 6, 1930, relating to an apparatus for recordation and reproduction of sound.

In the drawings:

Fig. 1 is a side elevation of a form of reproducer embodying the principles of my in-

vention, part thereof being shown with the casing removed for purposes of clearness.

Fig. 2 is a bottom plan view of the reproducer illustrated in Fig. 1.

5 Fig. 3 is a somewhat diagrammatic illustration of one of the arrangements of magnets and electric circuits which may be used in my invention.

10 Fig. 4 is a reduced view of the right half of the reproducer, as illustrated in Fig. 2, and is taken on a plane indicated by the line CC of Fig. 2.

15 Fig. 5 is a reduced view of the left half of the reproducer as illustrated in Fig. 1, and is taken on a plane indicated by the line BB of Fig. 1.

20 Fig. 6 is a side elevation of the body member of the reproducer illustrated in Figs. 1 and 2 illustrating the mounting of the stylus bar thereon and the rubber spacing ring and diaphragm.

25 Fig. 7 is a detail plan view of one form of torsion spring suitable for use in my invention.

Fig. 8 is a side elevation of the clamping ring of the reproducer illustrated showing another means for mounting the torsion spring.

30 Fig. 9 is a plan view of a diaphragm suitable for use in my reproducer.

Figs. 10, 11 and 12 are cross sectional views illustrating forms of diaphragms which may be used in connection with my invention.

35 Fig. 13 is a cross-sectional view of a diaphragm similar to that illustrated in Fig. 9, and is taken on a plane through the center thereof.

40 Fig. 14 is a cross-sectional view of a preferred form of throat for use in my reproducer and is taken on a plane indicated by the line AA of Fig. 5.

45 Referring to the drawings, Fig. 1 illustrates one embodiment of my invention in a reproducer having a body member 1 or principal part to which other parts are attached.

50 This body portion may be of either metal or wood and is preferably in the form of a disk having a central opening in which is mounted the sound tube 2 for the transmission of sound waves to any amplifying device to which the reproducer may be attached. As illustrated in Figs. 1 and 2, a diaphragm 3 is mounted on the body 1 by a clamping ring 4, the diaphragm being spaced from the body 55 1 by a rubber ring 5. This assemblage may be conveniently made by clamping the ring 4 against the body 1 by means of screws such as 6 and 7. In the form illustrated, the sound tube 2 passes through the body 1 and 60 terminates in the plane of the face of the body 1 adjacent to the diaphragm. For purposes of clearness, the sound tube 2 is not shown in Fig. 2.

The ring 5 is preferably removable and may be made of rubber or other suitable ma-

terial. This ring is placed between the diaphragm 3 and the face of the body 1 to space the diaphragm the correct distance from the face of the body 1 and from the opening of the sound tube 2. The ring 5, however, may be formed integral with the body 1 and of a predetermined thickness so as to definitely fix the distance between the face of the diaphragm 3 and the adjacent face of the body 1 or the opening in the sound tube 2. The clamping ring 4 may be recessed, as better shown by the dotted line 8 in Fig. 8 to accommodate both the diaphragm and the rubber ring 5. The clamping ring 4 is slotted to form a passage for the stylus bar 13 when the stylus bar is mounted in one of the ways later to be described.

Screwed, or otherwise rigidly fastened to the body 1 is a supporting plate 9 to which the ends of a torsion spring 10 are secured. 85 Intermediate the points of connection of the spring to the plate, the plate is recessed, as illustrated, the spring bridging the recess.

However, if desired, instead of using the plate 9 suitably spaced lugs 11 may be cast or fastened on to the clamping ring 4 as illustrated in Fig. 8.

The torsion spring, the purposes of which will now be described, may comprise a thin piece of metal. For example steel of 20/1000 of an inch thickness may be used.

In the present types of sound reproducers and recorders in which the stylus bar is usually actuated by a record, the stylus bar is usually mounted on pivots and has no tendency to return to its normal position after it has been actuated. Therefore it will lag appreciably behind the vibrations impressed upon it and return to its normal position only as a result of its being moved by the record or the diaphragm. When the diaphragm is so hampered it will not produce a true tone or faithful reproduction but a distorted wave. To eliminate this undesirable action I actuate my stylus bar with a torsion spring. 110

The end portions only of the torsion spring engage the plate 9 or the lugs 11, these end portions being provided with screw holes for fastening the torsion spring onto the plate 9. The stylus bar is rigidly secured to the spring, preferably at the center thereof, and extends to the center of the diaphragm. A suitable means of connecting the stylus bar to the spring is by means of a lug 12 rigidly secured to the stylus bar. This lug may project laterally and be provided with a bore to receive a stylus and a thumb screw to retain the stylus therein. As an example, a torsion spring of less width than its end or supporting portions may be used, the spring having a small central enlargement so that the stylus bar or lug supporting the same may be conveniently fastened thereto by screws. This type of spring is illustrated in Fig. 7. 125 A stylus bar so mounted can vibrate by twist-

ing the narrow portions of the torsion spring. For instance, in the case of reproduction of sound from lateral cut records the sound grooves of the record are lateral of the path of movement and the record transmits a lateral movement through the stylus to the stylus bar by twisting the stylus bar about the longitudinal torsional axis of the torsion spring. The width of the spring 10 in the direction of motion of the stylus is sufficiently great to prevent any lateral movement of the spring itself at the point of the support of the stylus bar, so that the spring itself allows only a torsional or twisting 15 movement similar to the movement which the stylus bar would have if it were mounted on pivots. At the same time, the stylus bar is returned to its normal position by the torsion spring no matter in what direction it 20 has been moved or twisted by the action of the record on the stylus. This return is rapid, the vibrating period or cycle of the stylus bar and spring assembly being in direct proportion to the breadth and thickness 25 and inversely proportional to the length of the torsion spring. I make the torsion spring relatively short and thick, using for instance, steel 20/1000 of an inch in thickness. Such a spring has such a high natural frequency of 30 vibration that it does not have any tendency to blur or distort the sound waves transmitted through the stylus bar to the center of the diaphragm. Further, it raises the pitch of the stylus bar 13 and actuates it while 35 keeping the pitch of the stylus bar higher than that of the human register. Therefore the stylus bar has no tendency to swing in unison with, or to impress its own period of vibration on the vibrations received from the 40 record.

Another point at which sound waves are distorted in many talking machines is at the center of the diaphragm where there is a combination of a slow moving diaphragm and 45 a slow moving stylus bar which must be overcome by the power transmitted from the record. The torsion spring described is of sufficient strength to actuate the diaphragm also. Thus the key note of the entire assemblage 50 as well as each part is raised above the audible range. This gives the stylus bar and the assemblage a period of vibration or key note which is out of the audible range of vibration and consequently the combined dia- 55 phragm stylus bar and springs do not synchronize with impressed vibrations and have no tendency to swing in unison with them or to impress their own period of vibration on them. Obviously, the same is true of the torsion spring itself. Therefore, vibrations 60 which are carried up the stylus bar to the diaphragm are substantially free from chatter, and any tendency of the stylus bar or the torsion spring to vibrate in unison with impressed vibrations and transfer the resultant 65

vibrations to the diaphragm so as to blur the sound reproduction or recordation is eliminated. Such vibrations as are impressed upon it to cause it to vibrate in unison therewith will be only such sounds as will not affect the 70 human ear, as they will be above the audible range. Since the stylus bar and diaphragm thus are actuated and are raised in pitch by a torsion spring of such a high period that they will not appreciably distort the impressed vibrations, I can employ a magnetically sensitive diaphragm, that is, a diaphragm which is composed of or includes soft metal and which diaphragm has practically 75 no period of vibration of its own. 80

In some cases, however, I prefer to use a diaphragm of spring tempered steel or other spring tempered material, preferably in the form of a disk mounted as a diaphragm in the diaphragm ring of the reproducer. In 85 such cases, due to the fact that the diaphragm has a spring action and will return to its normal position almost as rapidly as it is moved by the vibrations of the stylus bar, the stylus bar may be mounted on pivots in the usual 90 fashion and without a torsion spring. 95

For instance, the spring tempered dia- phragm in Fig. 13 has its own tendency to re- turn to normal position and to return the stylus bar and hold the stylus bar at a higher 95 pitch than the ordinary diaphragm would do and consequently, the stylus bar may be mounted on pivots, as stated.

As set forth in the objects of my invention, it is necessary to have a diaphragm so delicately poised that it will respond to very slight variations in tone or magnitude of vibration and at the same time of such resiliency that it is capable of swinging through a greater amplitude than the greatest ampli- 105 tude of vibration that will be impressed upon it when in use. When I speak of a resilient diaphragm, I mean one which will reach the limit of its greatest vibration substantially in 110 unison with the impressed vibration and which will return to its normal position as rapidly as the cycle of the particular tone which is being impressed. In other words, the diaphragm must not lag appreciably be- 115 hind the impressed vibrations or there will be what is known as distortion. This distortion, in reality resultants of the diaphragm tone caused by its lagging behind the im- pressed vibration, is overcome by the torsion spring, as described, and my magneto elec- 120 tric circuit, later to be described and a dia- phragm having no key note as a whole, but having a period of vibration below the aud- ible range. 125

I have found that many diaphragms of a single substance have a fixed period of vibration or a key note to which they will respond more readily than they will to any other pe- 130 riod of vibration. Further, I have found that a velvety softness can be imparted to the 135

sound waves leaving a diaphragm by having the working side of the diaphragm present a soft fibrous surface, blotting paper serving as a fairly good illustration of such soft fibrous surface. For example, a hard fiber diaphragm, one face of which is covered with blotting paper, may be used. In the case of reproduction of the human voice, for example, such a soft fibrous working surface on a diaphragm will give to the sound waves leaving the diaphragm a more natural human tone. Also it will give an improved tone to the sound wave of whatever instrument is being reproduced.

Further, I have found that if a diaphragm is divided into two or more diaphragms or portions by the use of a smaller diaphragm or by rings formed or riveted, or otherwise secured in place on the diaphragm, each of the portions will have a period of vibration of its own and the diaphragm will be in effect, a compound diaphragm having no key note as a whole.

I shall now discuss a number of diaphragms embodying the principles above enumerated.

The diaphragm illustrated in Figs. 9 and 10 has been divided into two or more diaphragms or areas by use of a ring or annulus 14 secured in place on the diaphragm by rivets 15 or otherwise. This ring, or rings, if more than one is used, may be of the same material as the diaphragm or of a stiffer material. A diaphragm with rings so mounted will have more than one period of vibration. From observation, it appears that the outer diaphragm or portion 16 will have a low period of vibration, the ring section or annulus 14 will have a higher period of vibration and the inner diaphragm or central circular portion 17 will have a still higher period of vibration. Each area responds to different periods of vibration and each area will respond more readily to its own key note. For this reason the diaphragm as illustrated has no key note to which it will respond as a whole.

I have found that a diaphragm divided into three diaphragms or portions as illustrated in Fig. 9 gives very desirable results in the separation of sounds of different frequencies of vibration. As a concrete example the comingling vibrations resulting from the voice waves of a quartet traveling up the stylus bar to the center of such a diaphragm appear to be separated and each voice brought out clear and distinct and separate from the other voices, the outer diaphragm being responsive to the voices in the lower register, and the middle diaphragm being responsive to the voices in the middle register and the inner diaphragm being responsive to the voices in the higher register.

Thus desired and distinct separation of different voice tones and different toned instruments or of a plurality of sounds hav-

ing different wave lengths is obtained. By the use of such a diaphragm, I have been able to distinguish two voices singing "in harmony".

To use this type of diaphragm effectively in my magneto electric reproducer it is only necessary that the ring 14 be magnetically sensitive. The material which I use for the diaphragm in such case may either be magnetic or non-magnetic, in fact, any material commonly used for diaphragms is satisfactory.

These rings will be operated on by the magneto and electric members of my reproducer and will give substantially the same results as though I had used a completely magnetic or magnetically sensitive diaphragm.

This type of diaphragm may be covered on one side by a soft fibrous material as above mentioned. This fibrous surface imparts to the tone produced by the diaphragm, especially in the case of reproduction of the human voice a more natural tone which I have not been able to produce with a diaphragm having a smooth or glazed working surface.

Fig. 10 is a cross-sectional view of this diaphragm with rings riveted in place on opposite sides. These rings divide the diaphragm into three diaphragms or portions for the purposes enumerated above. The diaphragm itself may be made of any substance commonly used for diaphragm or may be either magnetic or non-magnetic, as stated.

In Fig. 11 is illustrated a diaphragm, composed of two or more substances. For instance, the diaphragm may be composed of a material either magnetic or non-magnetic and a soft fibrous material 18 or of a hard fibrous material with a soft fibrous material or of mica and a soft fibrous material, the object being to secure a resilient diaphragm with a soft and roughened fibrous surface which produces clearer tones than the harsher or metallic side of the diaphragm.

Fig. 12 illustrates a diaphragm divided into three diaphragms or portions, each having its own key note and in addition has the advantage of a diaphragm composed of two or more substances as illustrated in Fig. 11. As stated, the outer portion appears to vibrate more in unison with the lower tones, the superimposed rings 19 in unison with tones of the middle register and the small inner portion responding more readily to tones of the upper register, for example, the soprano. The soft fibrous covering produces better and more natural tones in all registers and thus renders the diaphragm especially effective for reproducing the human voice clearly. In such a diaphragm the desired and distinct separation of the voice tones of different pitches is obtained and slurring and blurring are eliminated, or are so reduced, as to be unnoticeable. This soft fibrous surface is designated at 20.

carried on said diaphragm and dividing said diaphragm into a plurality of clearly defined portions, each of said portions having a different key note within the audible range, said element being magnetically sensitive and means for varying said flux for effecting actuations of said element and diaphragm.

3. A sound apparatus including means for producing magnetic flux, a diaphragm responsive to said flux, means including an element operatively associated with the diaphragm for effecting actuations of the same, and means including a member operatively associated with said diaphragm and said element for impressing on said diaphragm and element a period of vibration above the audible range.

4. In a sound apparatus a magnetically responsive element, means to produce a magnetic flux at each side of the center of the path of vibration of said element transverse to the path of movement of said element and spaced from the normal position of rest of said element said flux yieldably opposing vibrations of said element near its outer limits of movement, the effect of said magnetic force diminishing as the element comes near to its normal position of rest.

5. A sound translating apparatus including a vibratable element and means producing a magnetic flux in which said element moves during vibration for opposing movement of said element, said means including magnet poles positioned on longitudinally opposite sides of the center of the path of vibration of said element, and individually short circuited coils arranged on said poles.

6. A sound translating apparatus including a vibratable magnetically sensitive element, a magnet producing a flux across and at longitudinally opposite sides of the center of the path of vibration of said element, and coils in inductive relation to said magnet, said coils being unconnected in any extraneous translating circuit.

7. In a sound translating device, a vibratable element, said element being responsive to magnetic flux, and means to vibrate said element, magnets opposing movement of said element in each direction of vibration from its normal position of rest, said magnets being arranged at least one at each of the longitudinally opposite sides of the center of the path of vibration of said element and producing flux across said path of vibration.

8. In a sound translating device, a vibratable element, said element being responsive to magnetic flux, and means to vibrate said element, magnets arranged at least one at each of the longitudinally opposite sides of the center of the path of vibration of said element and producing flux across the said path, said magnets being of opposed polarity relative to each other, said magnets oppos-

ing movement of said element from its normal position of rest substantially equally in each direction of vibration.

9. A sound reproducing device including a sound diaphragm, said diaphragm being sensitive to magnetic flux and means to vibrate said diaphragm, opposed magnets arranged at opposite faces of said diaphragm and producing flux across the path of movement thereof for opposing moving of said diaphragm in each direction of its vibration.

10. A sound reproducing device including a vibratable sounding diaphragm, means to vibrate said diaphragm, a magnetically sensitive element connected to the diaphragm and vibratable therewith, magnets spaced apart and on longitudinally opposite sides of the center of the path of vibration of said element and producing flux across the path of vibration thereof, said flux opposing movement of said element and diaphragm in each direction of vibration.

11. A sound reproducing apparatus including a sound producing diaphragm adapted to be vibrated, means to vibrate said diaphragm, a vibratable element responsive to magnetic flux connected to said diaphragm, magnetic means for producing magnetic flux across the path of vibration of said element at longitudinally opposite sides of the center of said path, said flux yieldably opposing movement of said element and diaphragm substantially equally in each direction of vibration from their normal position of rest.

12. In a sound translating device, a vibratable element including conducting material whereby said element is responsive to magnetic flux, and means to vibrate said element, magnets for producing a magnetic flux across the path of vibration of said element at longitudinally opposite sides of the center of said path of vibration, said flux yieldably opposing movement of said element from its normal position of rest in either direction of movement from said position of rest.

13. A sound reproducing device, including a vibratable sounding diaphragm, said diaphragm being responsive to magnetic flux, means for vibrating said diaphragm, and means including magnets for producing a magnetic flux for yieldably opposing movement of said diaphragm substantially equally in each direction of vibration from its normal position of rest.

14. A sound translating device, including a vibratable member, said member being responsive to magnetic flux, and magnetic means arranged for producing a magnetic flux across the path of vibration of said member at longitudinally opposite sides of said path for opposing vibration of said member equally in each direction of vibration from its normal position of rest, and means comprising coils inductive relative with said magnets for varying the opposing effect of said flux,

said coils being unconnected in any extraneous translating circuit.

15. A sound translating apparatus, including a vibratable element, said element being magnetically responsive, and means including a magnet arranged for producing a magnetic flux across the path of vibration of said element for opposing movement of said element substantially equally in each direction of vibration from its normal position of rest, a stationary coil in inductive relation to said flux for effecting variations in said flux, said coil being unconnected in any extraneous translating circuit.

16. A sound translating device, including a vibratable element, said element being responsive to magnetic flux, magnets arranged for producing magnetic flux across the path of vibration of said element at longitudinally opposite sides of the center of said path, said flux yieldably opposing movement of said element in either direction of vibration, coils inductively associated with said magnets for changing the intensity of said flux, said coils being unconnected in any extraneous translating circuit.

17. A sound translating apparatus, including a vibratable element and means to vibrate said element, said element being responsive to magnetic flux, means including magnets arranged at longitudinally opposite sides of the center of the path of vibration for producing flux across said path for yieldably opposing movement of said element from its normal position of rest, and coils in inductive relation with said magnets, said coils being unconnected in any extraneous translating circuit.

18. A sound translating device, including magnetically responsive vibratable element, a plurality of magnets arranged to cause magnetic flux across the path of vibration of said element at longitudinally opposite sides of the center of said path, part of said magnets being arranged at one of said longitudinally opposite sides of said path center and part at the opposite side, coils on said magnets, said coils being unconnected in any extraneous translating circuit.

19. A sound translating device, including a vibratable member responsive to magnetic flux, means comprising a plurality of magnets for producing a field in which said member is adapted to move during vibration, coils on said magnets, said coils being connected with each other.

20. A sound translating device, including a vibratable member responsive to magnetic flux, sets of magnets positioned at longitudinally opposite sides of the center of the path of vibration of said member, coils in inductive relation to said magnets, the coils of one of said sets of magnets being connected with each other in a closed local circuit.

21. In a sound translating device, a vi-

bratable member sensitive to magnetic flux, magnets positioned at longitudinally opposite sides of the center of the path of vibration of said member, coils in inductive relation with said magnets the coils of at least one of said magnets at one of said sides of said path center being connected with the coils of at least one of the magnets at the other side and forming therewith a closed local circuit.

22. In a sound translating device, a vibratable member responsive to magnetic flux, opposed magnets positioned at longitudinally opposite sides of the center of the path of vibration of said member, the fluxes of said magnets opposing each other, coils in inductive relation to said magnets, said coils being unconnected in any extraneous translating circuit.

23. In a sound translating device, a vibratable member responsive to magnetic flux, opposed magnets positioned at longitudinally opposite sides of the center of the path of vibration of said member, coils in inductive relation to said magnets, the coils of the magnets at one of said sides of said center of the path of vibration being connected in a closed local circuit with the coils of the magnets at the opposite side.

24. In a sound translating device, a magnetically sensitive vibratable element, magnets arranged to produce magnetic flux across the path of vibration of said element at longitudinally opposite sides of the center of the said path of vibration thereof, coils in inductive relation to said magnets, said coils being connected together in a closed local circuit.

25. A sound recording device, including a vibratable element, said element being magnetically responsive, a translating element, said translating element being vibratable consequent upon vibrations of the first mentioned element, and means to vibrate said first mentioned element, means including magnets arranged for opposing magnetically the movement of one of said first mentioned elements substantially equally in each direction of vibration from its normal position of rest.

26. In a sound translating device, a diaphragm, a translating element vibratable consequent upon vibrations of said diaphragm, magnetic means yieldably opposing movement of said elements substantially equally in each direction of vibration from their normal position of rest.

27. In a sound translating device, a magnet, a diaphragm, a conductor carried by an annular portion of said diaphragm and disposed in the field of said magnet, and means for energizing said conductor whereby actuations of said diaphragm are effected.

28. In a sound translating device, a magnet, a diaphragm, an annular conductor ele-

ment carried by an annular portion of the diaphragm and concentric therewith, said conductor element being arranged for vibration in the field of said magnet, a coil on said 5 magnet, and means to energize said coil whereby vibrations of said conductor and annular portion of said diaphragm are effected.

29. In a sound translating device, a dia- 10 phragm, an element of conducting material carried by an annular portion of said dia- phragm and concentric with said diaphragm, magnetic means for producing a flux in which said element is adapted to move dur- 15 ing vibration, means to vary said element and flux to effect actuations of said dia- phragm.

30. In a sound translating device, a vibrat- 20 able diaphragm, a magnet producing a mag- netic flux, a magnetically responsive element carried by an annular portion of said dia- phragm and arranged to vibrate therewith and in said flux, said flux opposing movement of said diaphragm through the medium of 25 said annular portion of said diaphragm when the diaphragm is vibrated and means to vibrate said diaphragm.

31. In a sound translating device, a vibrat- 30 able diaphragm and an element including conducting material and forming a part of the face of the diaphragm, means comprising a magnet arranged to produce a flux in which said element is adapted to move dur- 35 ing vibration, and means to vary the inten- sity of said flux.

32. A sound translating device including 40 a magnetically sensitive vibratable element, means for vibrating said element, and means including opposed magnets arranged at lon- gitudinally opposite sides of the center of the path of vibration of said element and pro- 45 ducing flux across said path for yieldably opposing vibration of said element in each direction of vibration from its normal position of rest.

33. A sound reproducing device comprising 50 a magnetically sensitive sounding dia- phragm, means to vibrate said diaphragm, and means including magnets arranged at opposite faces of said diaphragm for yield- ably opposing movement of said diaphragm in each direction of vibration from its nor- mal position of rest.

55 In testimony whereof, I hereunto affix my
signature.

WALTER RICHMOND.

CERTIFICATE OF CORRECTION.

Patent No. 1,845,988.

Granted February 16, 1932, to

WALTER RICHMOND.

It is hereby certified that error appears in the printed specification of the above numbered patent requiring correction as follows: Page 2, line 123, for the word "on" read one; page 3, line 14, strike out "itself"; page 4, line 97, for "diaphragm" read diaphragms, and line 113, for "advantage" read advantages; page 6, line 123, claim 1, for "or" read of, and line 127, claim 2, for "translated" read translating; page 7, line 98, claim 11, for "or" read of; page 8, line 40, claim 18, before "magnetically" insert the article a, and line 56, claim 19, after "other" insert the words in a closed local circuit; page 9, lines 15 and 16, claim 29, strike out the words "element and" and insert the same after the word "said" in line 16, of same claim; and that the said Letters Patent should be read with these corrections therein that the same may conform to the record of the case in the Patent Office.

Signed and sealed this 22nd day of March, A. D. 1932.
